TRAVELER RING

Robert Edgar Pomeranz, P.O. Box 250, Sanford, N.C.

Filed Jan. 5, 1960, Ser. No. 58,933

Term of patent 14 years

(Cl. D47—5)

FIG. 1

FIG. 2

FIG. 3

FIG. 4

FIG. 5

FIG. 6

FIGURE 1 is a top plan view of the traveler ring embodying my design;

FIGURE 2 is a bottom plan view of FIGURE 1;

FIGURE 3 is a front elevational view of FIGURE 1;

FIGURE 4 is a rear elevational view of FIGURES 1 and 2;

FIGURE 5 is a right elevational view of FIGURE 1; and

FIGURE 6 is an enlarged partial sectional view taken substantially along the section line 6—6 of FIGURE 1.

I claim:

The ornamental design for a traveler ring, as shown.
